UNITED STATES PATENT OFFICE.

WES BAHNEY, OF SOUTH BEND, INDIANA.

DOOR-STOP.

1,094,414.

Specification of Letters Patent. Patented Apr. 28, 1914.

Application filed July 30, 1912. Serial No. 712,225.

To all whom it may concern:

Be it known that I, WES BAHNEY, citizen of the United States, residing at South Bend, in the county of St. Joseph and State of Indiana, have invented certain new and useful Improvements in Door-Stops, of which the following is a specification.

This invention relates to improvements in door stops and has for its particular object 10 to provide a device of this character that is simple in construction, easy to manipulate and inexpensive.

A further object is to provide a compact device that when folded lies closely to the 15 door.

These and other objects hereinafter set forth are attained by the means illustrated in the accompanying drawing; in which—

Figure 1 is a perspective view of my improved stop shown secured to one of the bottom corners of a door. Fig. 2 is a side elevation of Fig. 1, shown folded in full lines and open in dotted lines. Fig. 3 is a central vertical section through the stop and its 25 supporting bracket, and Fig. 4 is a front elevation of the supporting bracket.

Similar reference numerals in all of the figures of the drawing designate like parts.

This improved device is preferably constructed of sheet metal and embodies a supporting bracket 5 and a hinged stop plate 6. Said bracket 5 is provided with oppositely disposed knuckles 7, adapted to support the pintle 8, upon which is pivoted the stop plate 6. Said stop plate is preferably formed wider at the top than at the bottom and on its top edge is formed a knuckle 9 which fits between the knuckles 7 and is engaged by the pintle 8. The bottom edge of the stop 40 plate is preferably serrated as shown at 10, but it will be understood, that a rubber or other anti-slipping tip can be provided as a substitute for said serrated edge.

To retain the stop plate 6 in its operative 45 and inoperative positions, a flat spring 11 is secured at one end, in any suitable manner, to the bracket 5, the free end of said spring is adapted to lie in a recess 12 in said bracket

and engages the knuckle 9 of the stop plate 6, and said knuckle is preferably formed 50 with two flat faces 13 and 14, the former engaging the end of the spring when the stop-plate is raised or in its closed position and the latter face 14 is engaged by said spring when the stop plate is down or in its open 55 position. Thus in either position the stop-plate is held securely against movement other than a positive force. To facilitate the rais- 60 ing and lowering of said stop plate 6, it is provided with an extension 15, projecting 60 from one side, the same being preferably formed integral with said stop plate and is bent at right angles thereto, so that in either position of the stop plate said extension lies approximately in a horizontal position 65 whereby it can be engaged with the foot of the operator.

The bracket 5 is provided with a depend- 70 ing extension 16, which is slightly curved outward below the knuckles 7 to form a stop back of the stop plate 6, and is adapted to position said stop plate at the proper angle relative to the floor, and to prevent back- 75 ward movement of said stop plate other than is necessary to properly engage the floor.

Bracket 5 is, as above stated, preferably stamped from sheet metal and the blank is slotted adjacent its sides, as shown at 16', Fig. 4, forming two side portions which are rolled to form the knuckles 7, and a central 80 portion which forms the stop 16.

Constructed as above described, a simple, cheap, light and durable door stop is pro- 85 vided, and a stop that is neat in appearance not clumsy looking, and that can be oper- ated with the foot of the operator.

Having thus fully described the invention, what is claimed is:

1. A door stop, comprising a bracket, a stop-plate pivoted thereto and adapted to 90 move angularly relative to the face of the door, and means on said stop-plate which projects at right-angles beyond both of the faces of said plate whereby said plate can be adjusted with the foot to a locking or 95 unlocked position.

2. A door stop, comprising a bracket, a stop-plate pivoted thereto and adapted to move angularly relative to the face of the door, means on said stop-plate which projects at right-angles beyond both of the faces of said plate whereby said plate can be adjusted with the foot to a locking or unlocked position, and means for holding said plate

in its extreme positions against other than a positive force.

In testimony whereof I affix my signature in presence of two witnesses.

WES BAHNEY.
